UNITED STATES PATENT OFFICE.

OTTO PHILIPP, OF DRESDEN, GERMANY, ASSIGNOR TO ELEKTRO-
GRAVURE, GESELLSCHAFT MIT BESCHRÄNKTER HAFTUNG, OF
LEIPZIG-SELLERHAUSEN, GERMANY.

HYDRAULIC PRESS.

SPECIFICATION forming part of Letters Patent No. 769,181, dated September 6, 1904.

Application filed April 19, 1904. Serial No. 203,845. (No model.)

To all whom it may concern:

Be it known that I, OTTO PHILIPP, a citizen of Germany, residing at Dresden, Germany, have invented new and useful Improvements 5 in Hydraulic Presses, of which the following is a specification.

This invention relates to a hydraulic press operated by means of a spindle and so constructed that the press-cylinder, the reservoir, 10 and the seat for the inlet-valve are all carried by the movable platen.

The accompanying drawing represents a vertical section, partly in elevation, of my improved hydraulic press.

15 The numeral 1 represents the lower fixed platen of a hydraulic press, and 2 is an upper frame mounted upon posts 3 and provided with a depending perforated piston 4. This piston is shown integral with the frame; but 20 it may be formed from a separate piece bolted thereto. The hydraulic-press cylinder 5 is formed integral with the upper movable press-platen 17 and embraces the piston 4. The cylinder 5 is surrounded by the reservoir 6, 25 formed upon platen 17 and adapted to contain the liquid used to charge cylinder 5. A duct 7 connects the reservoir 6 with the interior of the cylinder 5. This duct is controlled by a valve 8, by which the communication between the reservoir and the cylinder may be 30 temporarily interrupted. The rod 9 of valve 8 is provided at its upper end with a head 10, supported by a sleeve 11, which is screwed into the pressure-spindle 12 and is packed, as 35 at 22.

The pressure-spindle 12 has a bore or socket 13, adapted to accommodate the head 10 during the descent and ascent of the spindle. The spindle is threaded, as shown, and is tapped 40 into a nut 14, secured to frame 2. A hand-wheel 16 permits the spindle to be rotated, so that it rises or falls within the bore 15 of piston 4. This bore constitutes the reduced section of the compression-chamber formed with 45 in cylinder 5 and is in communication with such cylinder.

The drawing illustrates the invention ap-

plied to a hand-press for the sake of simplicity; but any other power may obviously be employed. In lieu of the threaded pressure-spindle 12 a rack may be employed and the reciprocating movement of the spindle may be effected by a crank, a steam-piston, compressed air, electricity, &c.

Normally the platen 17, with its reservoir 5 and hydraulic cylinder 5, is supported upon the top of spindle 12 by means of a cross-head 19, which rests upon the spindle and is connected to the platen by rods 18. If during 60 operation the spindle is lowered, the platen 6 will follow by gravity while the machine runs light—i. e., until the die 20 strikes the work-piece 21—the cross-head 19 remaining seated upon the spindle. During this movement the valve 8, suspended by its head 10 from collar 65 11, will remain open, as shown, so that water may enter from reservoir 6 into cylinder 5 and charge the latter.

When the die 20 strikes the work-piece 21, the platen 17 can no longer follow the descent 70 of spindle 12, and the latter will therefore move downward alone. By this movement the collar 11 will descend beneath the head 10, so as to liberate the same and cause the valve 8 to close by gravity. The water contained 75 in the hydraulic cylinder 5 will thus serve as a transmission medium for conveying the pressure of the spindle to the base of the cylinder. Thus the platen 17 will be forced against the work-piece with a pressure the 80 force of which depends upon the ratio between the cross-section of spindle 12 and that of piston 4. Upon the upward movement the spindle 12 first rises alone until its upper end strikes the cross-head 19. Shortly before 85 the cross-head thus becomes engaged the valve 8 is opened by the elevation of head 10 through collar 11. After the spindle has contacted with the cross-head the latter, together with its platen 17, is raised by the spindle to its 90 highest position, while the water will flow through the open valve from cylinder 5, through duct 7, back into reservoir 6.

If desired, the reservoir 6 may be arranged

at the side of the cylinder, so that it does not surround the same. The reservoir may be cast integral with the platen 17, so that platen, cylinder, and reservoir are made in one piece, 5 or either of these parts may be made separate. In the latter case all parts are rigidly connected, so that they move in unison. By uniting the cylinder 5 and the reservoir 6 with the platen 17 the latter is loaded to advantage without increasing the weight of the press. The platen during the light running of the machine will, owing to its load, follow the descending spindle more readily, which insures a quicker and more positive working 15 of the press.

What I claim is—

1. In a hydraulic press, an upper platen provided with a cylinder and a reservoir,

which are carried by such platen, substantially as specified.

2. In a hydraulic press, the combination of a platen with a reservoir and cylinder carried thereby, a perforated piston entering the cylinder, a valve-controlled duct connecting the reservoir with the cylinder, a pressure-spindle adapted to support the platen and engage the perforated piston, means for supporting the spindle, and means for suspending the valve from the spindle, substantially as specified.

Signed by me at Dresden, Germany, this 30
31st day of March, 1904.

OTTO PHILIPP.
